UNITED STATES PATENT OFFICE

170,501

CRIBBAGE BOARD

Bert V. Hare, Wenatchee, Wash.

Application June 12, 1953, Serial No. 25,470

Term of patent 3½ years

(Cl. D34—5)

To all whom it may concern:

Be it known, that I, Bert V. Hare, a citizen of the United States, residing at Wenatchee, in the county of Chelan and State of Washington, have invented a new, original, and ornamental Design for a Cribbage Board, of which the following is a specification; reference being had to the accompanying drawings, forming a part hereof.

Figure 1 is a top plan view of a cribbage board, showing my new design.

Figure 2 is a side elevational view;
Figure 3 is a bottom plan view; and

Figure 4 is an end elevational view, taken from the left of Figure 2.

I claim:

The ornamental design for a cribbage board, as shown.

BERT V. HARE.
